[57] CLAIM

The ornamental design for a rattle walker, as shown and described.

DESCRIPTION

FIG. 1 is a front elevational view of the rattle walker showing my new design;

FIG. 2 is a rear elevational view thereof;

FIG. 3 is a left side elevational view thereof;

FIG. 4 is a right side elevational view thereof;

FIG. 5 is a top plan view showing a use thereof;

FIG. 6 is a bottom plan view thereof;

FIG. 7 is an isometric view thereof; and,

FIG. 8 is a perspective view in use thereof, the broken line showing of a walker is for illustrative purposes only and forms no part of the claimed design.

*FIG. 1**FIG. 2**FIG. 3*

FIG. 4

FIG. 5
